UNITED STATES PATENT OFFICE.

JOHN W. JOHNSTON, OF TREMPEALEAU, WISCONSIN.

BLOW-TORCH.

1,108,436.

Specification of Letters Patent. Patented Aug. 25, 1914.

Application filed September 11, 1911. Serial No. 643,805.

To all whom it may concern:

Be it known that I, JOHN W. JOHNSTON, a citizen of the United States, residing at Trempealeau, in the county of Trempealeau 5 and State of Wisconsin, have invented a new and useful Improvement in Blow-Torches, of which the following is a specification.

My invention relates to improvements in blow torches and more particularly to that 10 class wherein the torch is detachably applied to a furnace for convenience in heating soldering irons, receptacles and other devices.

The primary object of this invention is to provide a stand for the blow torch into 15 which the blow torch can be locked with its burner applied to the furnace, said stand being portable so that it can be carried by a workman.

Among additional objects of this invention 20 are, simpler construction and means for utilizing the heat of a blow torch more effectively than in prior devices.

In the accompanying drawings forming part of this specification, Figure 1 is a perspective view of a blow torch having my improvement applied thereto; Fig. 2 is a plan of the furnace floor, a detail of the bail and of the torch being illustrated; Fig. 3 is a side elevation of an elbow tube of the furnace; Fig. 4 is a section of Fig. 3 taken upon the line A—A, Fig. 5 is a side elevation of a detail of the stand showing a furnace for heating a receptacle containing solder or other material applied thereto, and Fig. 6 is 35 a section of Fig. 2 on the line B—B.

In the drawings A represents a blow torch of usual construction having an ordinary burner tube 2, and B represents a stand for carrying a blow torch on which is mounted 40 a furnace C. The furnace is provided with a floor 3 made of sheet metal or other suitable material having vertical side flanges 4 and a serrated forward ledge 5, the latter being adapted to hold the shanks of soldering irons such as 6, while the irons proper 45 are resting in the furnace. To the floor 3 is detachably secured an arched plate C forming the roof of the furnace having its inner end partly closed and its opposite end open. 50 The lower side edges 7 and 8 of the arched plate are provided with pins 9 which are adapted to be engaged in perforations in the flanges 4 to hold the plate in place. The action of contracting the lower edges on the 55 open ends of the plate withdraws the pins 9 from the flanges 4 leaving the plate free to

be removed from the stand. The floor 3 near the inner end of the plate has an opening 10 below which depends an elbow 11 which connects with the burner of the blow torch. A 60 deflector 12 is formed integral with the elbow 11 lying directly below the opening 10 of the floor 3 and is triangular in form having one of the angles pointing downward and the sides thereof serving to bifurcate the 65 flame issuing from the burner of the blow torch and deflect the bifurcations through the opening 10 toward the two sides of the space below the roof of the furnace. The upper end of the elbow has a flange 13 which 70 is secured by bolts 14 to the lower surface of the floor 3. The floor 3 is supported upon four standards, 15, 16, 17 and 18, each of which is extensible being made in two sections, one of which is slotted at 19 to receive 75 a set bolt 20 for the purpose of binding the sections together and holding them in vertically adjusted position. The lower ends of the standards are secured by bolts 21 to a tray D on which the blow torch A is placed 80 and is held with its burner tube 2 in the elbow 11 by means of clamps 22 and 23 which are secured to the tray by means of thumb-bolts 24 with their ends over-lapping the flange 25 on the base of the blow torch A. 85 The forward pair of standards 17 and 18 are inclined from the tray back toward the floor of the furnace for the purpose of bracing the furnace and imparting stability to it.

The connections between the lower ends of 90 the standards by means of the bolts 21 and between the upper ends of the standards and the floor of the furnace by means of the bolts 26 are pivotal so that the height of the floor of the furnace above the tray may be 95 varied by adjusting the lengths of the standards. When desired a bail 27 can be secured to the floor of the furnace as illustrated in Fig. 1 for carrying the blow torch and furnace.

It is obvious that other forms of furnaces 100 may be employed and used for other purposes than heating tools. In Fig. 5 I have illustrated one of these other forms in which the furnace is in the shape of a collar 28 placed over a pair of outwardly extending flanges 29 and 30, extending across the floor 105 of the furnace for holding said collar in place. Into this collar a melting pot 31 may be placed for melting solder or heating any 110 material desired. The lower edge of the collar is substantially square and slotted at 32

for the purpose of forming a vent at each side of the stand for the egress of gases issuing from the blow torch.

It will be noted that the flanges 29 and 30 serve to form lateral supports for the sides and end of the roof of the furnace C, also vertical supports for the shanks of soldering irons or other tools which are placed in the furnace to be heated. In the 10 use of the roof of the furnace C and of the sleeve 28 or any other form of furnace used with this device the flame is directed in such a manner that its heat is applied most advantageously to the device which is heated 15 in the furnace, the bifurcating of the flame serving to perform this function.

In accordance with the patent statutes I have described the principles of operation of my invention together with the apparatus 20 which I now consider to represent the best embodiment thereof but I desire to have it understood that the construction shown is only illustrative and that the invention can be carried out by other means and applied 25 to uses other than those above set forth within the scope of the following claims.

Having described my invention, what I claim as new and desire to protect by Letters Patent is:—

30 1. A device of the class set forth, comprising, in combination, a portable blow torch having a body and burner tube, a stand having a tray for carrying said torch, clamps on said tray for adjustably and detachably securing said body thereto, a furnace on said stand above said torch, and an elbow tube depending from said furnace and with the lower end of which said burner tube is adapted to be connected.

40 2. A device of the class set forth, comprising, in combination, a blow torch having a burner tube, a furnace above said torch, an elbow connected between said furnace and

tube through which the flame from said burner tube is conducted into said furnace, 45 and a stand supporting said blow torch and furnace adjustably to vary the height of the lower end of said elbow to receive the end of said burner tube.

3. A device of the class set forth, comprising, 50 in combination, a blow torch having a burner tube, a furnace above said torch, an elbow adapted to form a connection between said furnace and tube to conduct the flame from the burner tube 55 upwardly into said furnace and a stand for supporting said furnace having a tray below to support said blow torch, said tray being adjustably secured to said stand to vary the distance between said tray and furnace and 60 admit the burner tube into the lower end of said elbow.

4. A device of the class set forth, comprising, 65 in combination, a blow torch having a burner tube, a furnace above said torch, a detachable elbow secured to the floor of said furnace, said elbow having a depending lower end to which said burner tube is adapted to be adjusted and a deflector formed integral therewith and extending 70 across the upper end of its passage and adapted to divide a current of heat passing upwardly through said elbow from said burner tube, a stand for supporting said furnace having a tray adapted to support 75 said torch and clamps pivotally secured to said tray for detachably holding the body of said torch on said tray.

In testimony whereof, I have signed my name to this specification, in the presence 80 of two subscribing witnesses.

JOHN W. JOHNSTON.
